UNITED STATES PATENT OFFICE.

WILLIAM J. LANE, OF POUGHKEEPSIE, NEW YORK.

SUPPORT FOR MOVING BODIES.

SPECIFICATION forming part of Letters Patent No. 501,949, dated July 25, 1893.

Application filed July 25, 1892. Serial No. 441,184. (No model.)

To all whom it may concern:

Be it known that I, WILLIAM J. LANE, a citizen of the United States, of America, residing at Poughkeepsie, in the county of Dutchess 5 and State of New York, have invented certain new and useful Improvements in Supports for Moving Bodies, of which the following is a specification.

In Letters Patent of the United States dated 10 June 21, 1892, No. 477,558, I have shown and broadly claimed an apparatus, in which a bar pivoted on a base, is connected to an arm in such a manner that when the bar is inclined, the arm is inclined equally but in an opposite direction, so that the free end of the arm, moves in substantially a straight line, and may support a body so moving.

My invention hereinafter set forth, is an improvement in which the same principle of 20 construction is embodied, but with substantially different connections, by means of which the bar is maintained in its changing relation to the base, and the arm and bar in their changing relations to each other.

25 I have illustrated my invention in the accompanying drawings, in which—

Figure 1 represents the invention in perspective. Fig. 2, shows an edge view thereof. Fig. 3, shows a rear elevation.

30 In the figures, a base of convenient form and representative of any suitable base, is shown at A. It consists of a metal plate, the ends of which are bent inwardly, to form an offset at b, the ends being provided with holes 35 2, for securing it in place. The recess between the offset and behind the plate, as shown in Fig. 1, allows space for the pivoted bar D. This bar is pivoted upon a sleeve held on a bolt d set in the plate, so as to move in either 40 direction in plane parallel with that of the plate, its range of movement being limited only by the offsets.

To the upper part or free end of the bar, is pivoted a wheel E, by a sleeve held by a bolt e. 45 The wheel carries an arm F, which is firmly secured and bolted to the wheel, the arm and wheel moving together on the bar. The periphery of the wheel is grooved preferably with a double groove, 3, 3. The arm has a 50 hole in its lower or free end, as indicated at 4, by means of which the moving supported or suspended body may be attached.

For convenience of illustration, I represent the device, as supporting a sliding door H, which requires to be moved in a substantially 55 horizontal line, although the movement may be in a slight curve highest in the center, or the reverse. It may be desirable to have the line of movement of the end of the arm, trace a curve slightly higher at the ends, to compensate for the spring of the parts when the bar and the arm are inclined, or extended, when it is desired to carry door or other load in a straight line. It will be understood that for such a door, the apparatus would be used 65 in duplicate.

The door or other object is suspended by pivotal connections, with the lower end of the arm or arms, and the distance between this pivot in the lower end of the arm and the 70 pivot of the wheel or segment E (when movement of the suspended body in a right line is required) is the same as the distance between the pivot e and the pivot d. Variations from this equality will give curved lines of movement, in a vertical plane, when bar and arm are moved as above indicated. In order to maintain the bar and arm in these relations and to support them upon the base, I have in this 75 invention provided direct connections between the bar and the base on which the bar is pivoted; and these direct connections, also maintain the relations between the bar and the arm.

It will be observed that the wheel E, is a 85 fixed part of the arm F. On the base, as a fixed part thereof, is a circular or nearly circular rim, which for convenience, I call a segment, and have marked it G. Its center is the pivot d. It might be a complete wheel, but the part 90 cut off is not necessary. As shown, it consists of a simple rim of metal, having a flange g, which with the base plate, to which it is fixed, forms a channel or groove for the rope. These two parts, the arm with its wheel and the base 95 having a circular rim, may be connected in other ways; but as shown, they are connected by a rope (preferably a wire rope). I might use a chain or a thin elastic strip of metal, but the wire rope is better. This rope is connected to both parts as shown. For convenience I use a single piece of wire rope, one end of which is attached to the stud 10, on the base plate, the rope being carried up 100

around the grooved periphery of the segment G, and thence directly to the wheel E, over which it is wound in one of the grooves to the point 11, where it is led into a notch 12, in the rim, and through a hole in the wheel to the rear. Across this face it is laid in a notch 13, in the rim, from which it is wound in the other groove in the wheel E, and carried down to the groove of the segment G, and this end is attached in the same manner as the other.

When the device is designed to sustain a door, or other load requiring to be moved in a straight line, or approximately straight, the proportions of the parts shown in the drawings, should be substantially observed. The equality of the arms, necessary for this purpose has been noted. The wheel as shown in the drawings, has a diameter equal to one half of the diameter of the segment. In the construction shown in which the support is made by means of a wire rope, the measurements are taken from the center of the rope lying in the groove of the wheel or segment, diametrically across to the center of the rope on the other side.

The rope is prevented from slipping on the wheel E, by means of a screw 14, through the end of which it passes.

30 The bar is provided at its lower end with a slot 15, in which is fitted a block m. This block fits snugly at the sides but has spaces for endwise movement in the slot. The block m is pivoted on the sleeve of the bolt d, which has a washer 16 extending laterally over the bar. A screw 17, is inserted through a hole in the end of the bar, and its end is screwed into a hole tapped into the end of the block, so that by turning the screw, the wire rope 40 may be put under the necessary tension.

While I have described the particular form of connection between the base and the arm,

I do not limit my invention to the particular connections. My invention differs from that shown in my patent aforesaid, in this, that in 45 the said patent, the bar is supported on the base, through connections with another bar, while in the present case, the connection is direct between the bar and the base.

The door indicated at H, is supported by a 50 hook p, provided with a threaded shank. The shank is inserted in a hole in the door, as usual, and has a serrated nut 18, located in a recess and accessible, by means of which the door may be adjusted in height. The hook 55 connects with the hole in the lower end of the arm.

I claim—

1. An apparatus for supporting moving bodies consisting of a bar pivoted on a suitable base, and an arm pivoted on the free end of said bar, a wheel or segment on the arm, and a rim on the base and direct connections between the wheel and rim, substantially as described. 60

2. In combination with a bar D, pivoted on a base, a supporting arm F, pivoted to the free end of said bar, a curved bearing secured to the arm F and a curved bearing G secured to the base, and flexible connections between 70 said bearings arranged to conform thereto, substantially as described. 65

3. In combination with a suitable base having a segment, a bar pivoted on said base, an arm provided with a wheel, pivoted on the 75 free end of said bar, and a rope or chain connection between said wheel and said segment, substantially as described.

In testimony whereof I affix my signature in presence of two witnesses.

WILLIAM J. LANE.
